UNITED STATES PATENT OFFICE

2,482,551

COMBINATION IGNITER AND FLAME
DETECTORTheodore Y. Korsgren, Winnetka, Ill., assignor
to Stewart-Warner Corporation, Chicago, Ill.,
a corporation of Virginia

Application October 8, 1945, Serial No. 621,142

5 Claims. (Cl. 158—28)

1

The present invention relates to heaters and more particularly to a mechanically simple dual purpose device which serves as a flame detector and also as an igniter for instituting combustion.

In heaters or furnaces of the liquid or gaseous fuel burning type, some means is required for starting combustion. This means usually takes the form of a high tension electric spark or a gas pilot flame or in some cases a hot wire low voltage resistance element. Frequently also, particularly in gas burning heaters, the ignition means takes the form of an electric spark which is used only occasionally for starting a gas pilot, the gas pilot serving as the principal igniter. In addition to the ignition mechanism, heaters and furnaces usually have what is known as a flame detector. The purpose of this device is to operate controls such that the fuel cannot be turned on or will be turned off if it is already on, whenever the pilot is out or combustion in the main burner is not taking place.

It is therefore an object of the present invention to provide a novel device which serves both as an igniter and as a flame detector.

A further object of the present invention is to provide a novel device which interrupts the fuel supply to a furnace or heater with which it is used if combustion ceases, or if the device is not in condition to function properly as an igniter.

A further object of the present invention is to provide a novel device for accomplishing the above set out objectives at lower cost and with greater reliability than known devices with which I am acquainted.

Still another object of the present invention is to provide a novel combined igniter and flame detector in which the igniter element operates directly on commonly used line voltages.

Other objects and advantages will become apparent from the following description of a preferred embodiment of my device which is illustrated in the accompanying drawings.

In the drawings, in which similar characters of reference refer to similar parts throughout the several views:

Fig. 1 is an enlarged longitudinal sectional view of one form of a device embodying features of the present invention;

Fig. 2 is a longitudinal sectional view of a portion of the device illustrated in Fig. 1, drawn to larger scale. This view is taken along the line 2—2 of Fig. 1 in the direction indicated by the arrows;

Fig. 3 is a transverse sectional view taken in

2

the direction indicated by the arrows along the line 3—3 of Fig. 2;

Fig. 4 is a somewhat diagrammatic longitudinal sectional view of a portion of a heater illustrating the device shown in Figs. 1, 2, and 3 in use; and

Fig. 5 is a fragmentary longitudinal sectional view of a device embodying an alternative form of the present invention. The portion of the device broken away in Fig. 5 may be identical to the similar portion of the alternative device illustrated in Fig. 1.

Referring to Fig. 1 of the drawings, the igniter comprises a generally cylindrical shell or thimble 10 having a comparatively thin wall and formed integrally with a somewhat heavier hexagonal head 12 at one end. Adjacent the hexagonal head the tubular portion is provided with threads 14 for easy attachment of the device in a heater, such as is indicated generally by the numeral 16.

The body portion comprising the thimble 10 and head 12 is formed of heat and corrosion-resistant stainless steel or other alloy, which is adapted to be operated in a somewhat corrosive atmosphere at red heat.

For convenience, the cylindrical cavity within the thimble 10 is indicated by the numeral 18 and this cavity is connected to a chamber 20 of somewhat larger diameter located within the head portion 12.

The thimble 10 is provided internally with a heating element 22 located within the cavity 18 which when energized heats the shell 10 by radiation and by conduction through an inert gas which fills the thimble 10. This heating element comprises a wire 24 of tungsten, tungsten alloy, or the like, wound in a helical groove formed in a ceramic core 26. The core is preferably made of thorium oxide, aluminum silicate or other electrical insulating material which is adapted for operation at high temperatures. The core 26 has an axial opening 28 threaded at one end to receive a terminal stud 30. This terminal stud extends outwardly through an opening 32 of comparable size formed at the lower end of the shell 10 by necking the shell down to comparatively small diameter. For convenience in assembly, the stud is formed with a groove 34 such that after the stud has been inserted through the opening 32 and has been secured to the shell by brazing, as at 36, the portion of the stud which extends beyond the end of the igniter can be broken off.

The end of the wire 24 adjacent the terminal stud 30 is enclosed within a pad coil 38 which

extends through a transverse hole 48 drilled in the stud 30. This pad coil serves to provide good electrical conductivity between the wire 24 and the stud 30, and serves to lower the electrical current load carried by the wire at the point where it passes through the stud, thereby preventing overheating of the wire at the enclosed portion. The pad coil also provides a connection less easily broken than if the wire 24 were secured directly to the stud.

The portion of the core 26 around which the coil 24 is wound is sufficiently smaller in diameter than the opening 18 so that the wire 24 cannot become grounded by touching the wall of the thimble. To keep the core in alignment, it is provided at its lower end near the stud 30 with a flange 42 which rests against the face of the inwardly tapering side wall of the thimble 18 while a head 44 having a circumferentially extending groove 46 is formed at the opposite end of the core and is of such size that it fits loosely within the thimble. The head 44 is formed with a sector shaped slot 48 in one side thereof into which is fitted a complementarily shaped block 50 of similar material. This block when in place in the slot provides the head with a substantially continuous circumference.

The head 44 has an axial bore 52 into which a tube 54 is loosely fitted so that a small amount of relative longitudinal movement between the parts brought about by thermal expansion and contraction is not inhibited. The upper end of the wire 24 is provided with a pad coil 56, the lower portion of which lies against the tube 54 and in the sector shaped slot 48 while the upper end and the enclosed wire 24 are wrapped around the tube 54 about two turns and then extended into a slot 58 in one side of the tube 54. Thus the upper end of the pad coil is enclosed within the tube, this portion of the tube subsequently being pinched flat as at 60 to hold the pad coil in place and serve as an electrical connection between the tube and the coil.

After the heating element has been assembled, as above described, the sector shaped block 50 is put in place in the longitudinal slot 48 and is secured by a split ring 62 located in the circumferential slot 46. As will be seen in Fig. 3, the inner end of the sector shaped block 50 does not extend quite to the tube 24 but leaves sufficient space to accommodate the wire 24 and pad coil 56.

Slightly outward of the pinched portion 60, the tube 54 is provided with a small hole 64 to provide a gas communication path between the cavity 18 and the interior of the tube 54. Just above the hole 64 the tube 54 is sealed within a glass bead 66, the outer portion of which is sealed to a metal cup 68. The outer portion of the cup has a reverse bend as at 70 and a longitudinal extending portion 72 which lies against the inner wall of the upper portion of the thimble 18. The extreme end of the portion 72 is flanged over and brazed to the body portion of the igniter as at 74.

In order to preserve a gas-tight relationship between the tube 54 and the metal cup 68, the tube, the cup and the glass bead 66 are selected from materials having similar coefficients of expansion.

The upper end of the tube 54 is connected to a small Sylphon type bellows 76, the opposite end of which carries an insulating button 78 adapted to raise the lower blade 80 of an electric switch 81 when the bellows is extended. The

blade 80 carries a contact button 82 which cooperates with a similar button 84 located at the end of a second contact strip 86. These strips are insulated from each other by a block of suitable insulating material 88, are connected by a plastic rivet, and are attached to the side wall of the head 12 by means of terminal screws 90 and nuts 92 which are insulated from the head 12 by suitable insulating washers or strips 94. It is apparent from the above that when the bellows 76 is contracted, the contacts 82 and 84 will be separated and therefore no circuit will be established between the two terminals 80. Upon the bellows 76 being extended a predetermined amount, however, the contacts 82 and 84 are brought together, thus completing a circuit between these terminals.

The tube 54 in a position slightly below the bellows 76 is welded to a branch tube 96 which is bent outwardly, upwardly, inwardly and finally into a position in axial alignment with the tube 54, the bends just described being for the purpose of clearing the bellows and switch.

After the device has been assembled as described, the upper end of the tube 96 is connected to a vacuum pump to evacuate the chamber 18, the tube 54, the bellows 76, and the branch tube 96. After evacuation the system is refilled to approximately atmospheric pressure with a suitable lamp gas, such as a mixture of approximately 87 per cent argon and 13 per cent nitrogen, for instance. The upper end of the tube 96 is then pinched and sealed off with solder as at 98 and is soldered to a short length of metal braid 100 which extends axially through and is soldered to a terminal stud 102, this stud being secured by insulating washers 104 and a nut 106 to a sheet metal cap 108. The lower end of this cap is flanged outwardly as at 110 and is secured to the upper end of the head 12 by swaging as at 112. The bellows 76 and electric switch indicated generally by the numeral 81 are ventilated by air which can pass through a plurality of holes 114 formed in the head 12.

When the igniter terminals of the above device are suitably connected, that is, by a lead 116 secured to the terminal 106 by a nut 118 and by the other side of the circuit being grounded, the coil 24 heats up much like the filament in an ordinary incandescent light bulb and quickly heats the lower portion of the shell 18 to a temperature sufficiently high for the ignition of a mixture of air and a liquid or gaseous fuel. At this temperature the inert gas surrounding the coil is heated to a high temperature and increases the pressure within the chamber 18. This pressure is communicated through the opening 64 to the interior of the tube 54 and thence to the bellows 76. The bellows are therefore elongated and raise the switch blade 80 and complete a circuit between the terminals 80 and 82 by way of switch blade 80, contacts 82 and 84 and blade 86.

In Fig. 4 I have shown the igniter suitably arranged in one type of heater. This heater comprises a spray nozzle 120 mounted in a fitting 122 which in turn is connected by a tube 124 through a bulkhead type fitting 126 to a magnetic shut-off valve 128, the inlet side of the magnetic valve being connected to a source (not shown) of fuel under pressure.

The nozzle 120 is mounted in a plate 130 which carries a conical type combustion chamber 132 located within an air plenum chamber 134. Air is brought tangentially into this plenum cham-

ber by way of a tube 136 connected to a fitting 138 welded to the side wall of the chamber 134.

Beneath the nozzle 120 the cone 132 has an opening 140 which communicates with a pocket 142 in which the thimble 10 of the igniter is located, the igniter being threaded into an opening in the plate 130.

The outlet end of the plenum chamber 134 is connected to a heat exchanger 143 of any suitable type, while a jacket 144 surrounds and encloses the heat exchanger and burner. Ventilating air is introduced through a duct 146 connected to the jacket 144 by an adapter 148 so that air passes around the burner and through the heat exchanger so as to absorb heat from combustion taking place at the burner 132. The opposite end of the heater, including a portion of the heat exchanger and the heater exhaust connection, are not shown since the present invention is directed to the combination igniter and flame detector rather than to any specific type of heater.

The electrical circuit shown in Fig. 4 comprises a source of electrical energy indicated for convenience by the battery 150, although usually 60-cycle alternating current at about 110 volts potential is more generally used, one side of which is grounded as at 152, while the other side is connected through a master control switch 154 to a wire 156 which in turn is connected through a thermostatic igniter switch 158 to a wire 160, this wire leading to the terminal 102 by way of a bulkhead type electrical conductor 162.

One of the terminals 90 is connected by a lead 164 to the wire 156 at a point between the switches 154 and 158, while the other terminal 90 is connected by a wire 166 to the terminal 168 of the magnetic valve 128, the other side of this valve being grounded. The valve 128 is of the type which is closed until energized and recloses as soon as de-energized. The master switch 154 is preferably of the over center or snap action type which remains closed or open as set. The thermostatic igniter switch 158 may be of the bimetal type sensitive to the temperature of the ventilating air downstream of the heat exchanger 143, so that this switch is normally closed when cold and opens the circuit therethrough when the temperature of the ventilating air rises sufficiently to indicate that combustion is well started.

The device illustrated in Fig. 4 operates in the following manner: Whenever heat is desired, switch 154 is closed. This energizes the igniter by way of wire 156, igniter switch 158, wire 160, and bulkhead terminal 162 to the terminal 102 of the igniter, through braid 100 and branch tube 96, to the tube 54 and thence to pad coil 56 and heating wire 24 to ground by way of pad coil 38, terminal stud 30, and shell 10.

In a matter of ten seconds or so, the igniter will have reached igniting temperature and will have heated the inert gas in the space 18 and raised the pressure thereof, which communicates by way of opening 64 and tube 54 to the bellows 76. This causes the bellows to elongate until the knob 78 brings contact 82 against contact 84. As soon as this happens, the magnetic valve 128 is energized by way of lead 164, terminals 90 and 92 and switch 81, and lead 166 to the terminal 168 of the magnetic valve and thence to ground. The valve therefore opens and permits fuel under pressure to pass therethrough and through the tube 124 to the spray nozzle 120. The fuel issues from the nozzle in a fine mist which mixes with

the combustion air, the mixture being ignited by the hot tip of the thimble 10.

The hot products of combustion thus formed pass through the heat exchanger and to the exhaust not shown, with the result that ventilating air passing inwardly through the duct 146 and through the heat exchanger is quickly raised in temperature until the thermostatic igniter switch 158 opens, thereby de-energizing the igniter.

Even though the igniter is de-energized, the temperature of the inert gas does not decrease sufficiently to open the switch 81 because the heat of combustion keeps the igniter thimble 10 quite hot. On the other hand, if at any time combustion ceases, the thimble 10, which is of comparatively thin metal, cools quickly so that the temperature of the inert gas drops sufficiently to permit the bellows 76 to contract enough to open the switch 81 very soon after combustion ceases. As soon as the switch opens, the magnetic valve 128 is de-energized, thereby interrupting the flow of fuel to the nozzle 120.

In the above description of the operation of the heater and control mechanism, it is assumed that a source of air under pressure is connected to the duct 146 and to the tube 136 so as to produce a flow of both ventilating air and combustion air to the heater. Such a source of air under pressure may comprise one or more blowers or may comprise connections to a scoop or ram on an airplane.

Under some conditions it may be desirable to locate the switch 81 remotely from the igniter. Such a scheme is illustrated in Fig. 5. In this embodiment of the invention the tube 54 extends through the glass bead 66 as in the previous embodiment and is provided in the space between the bead 66 and the terminal 106 with a U-bend 170 to introduce resiliency to take up slight end-wise expansion and contraction between the terminal 106 and the bead 66. Above the U-bend 170, the tube 54 extends through the terminal 106 and is soldered thereto as at 172. From the terminal the tube 54 continues for any reasonable length and at its end is connected to a bellows 176 similar to the bellows 76. These bellows are provided with an insulating knob 178 which operates a leaf type switch 181 similar to the switch 81. It operates in the same manner as switch 81 and may be connected in the circuit illustrated in Fig. 4 in place thereof.

Although I have shown only one electrical circuit for taking advantage of the features of the present invention and have shown switches of only the single pole single throw type, it will be appreciated that this device is adapted for use in all types of flame detector circuits; and that when appropriate in such circuits, it is intended that the device of the present invention be provided with gang type switches, if necessary, and that these switches can be either of the normally open or normally closed types and that they may be arranged so that there is a temperature differential between operation of certain of the switches and operation of others of the switches. This, of course, can be accomplished in a well known manner by so arranging the switches that the knob 78 or 178 must move farther to operate some switches than to operate others.

Having described my invention, what I claim as new and useful and desire to secure by Letters Patent of the United States is:

1. A combination igniter and flame detector comprising, an electric resistance type heating

element adapted to be heated to incandescence, a metal envelope enclosing said heating element and slightly spaced therefrom so that said envelope may be heated to ignition temperatures by said heating element, means for connecting electric leads to said heating element, a movable member, a pressure responsive device adapted to move said member upon a change in pressure, passage forming means connecting said pressure responsive device to said envelope so that said envelope said pressure responsive device and the last said means comprise a single gas tight system, and a quantity of inert gas filling said system.

2. A combination igniter and flame detector comprising, an electric resistance type heating element adapted to be heated to incandescence, a metal envelope enclosing said heating element and slightly spaced therefrom so that said envelope may be heated to ignition temperatures by said heating element, means for connecting electric leads to said heating element, an electric switch, a pressure responsive device adapted to operate said switch upon an increase in pressure, passage forming means connecting said pressure responsive device to said envelope so that said envelope said pressure responsive device and the last said means comprise a single gas tight system, and a quantity of inert gas filling said system to substantially atmospheric pressure.

3. In a combination igniter and flame detector, an electric resistance type heating element adapted to be heated to incandescence, a metal envelope enclosing said heating element and slightly spaced therefrom so that said envelope may be heated to ignition temperatures by said heating element, means for connecting electric leads to said heating element, an electric switch, a pressure responsive device adapted to operate said switch upon an increase in pressure, a tube connected at one end to said pressure responsive device and extending into said envelope, a glass to metal seal between said tube and said envelope so that said envelope said pressure responsive device and said tube comprise a single gas tight system, and a quantity of inert gas filling said system to substantially atmospheric pressure.

4. A combination igniter and flame detector comprising, an electric resistance type heating element adapted to be heated to incandescence, a heat and corrosion resistant metal envelope en-

closing said heating element and slightly spaced therefrom so that said envelope may be heated to ignition temperatures by said heating element, means for connecting electric leads to said heating element, an electric switch, a pressure responsive device adapted to operate said switch upon an increase in pressure, a tube connected at one end of said pressure responsive device and extending into said envelope, a glass to metal seal between said tube and said envelope so that said envelope, said pressure responsive device, and said tube comprise a single gas tight system, a quantity of inert gas filling said system to substantially atmospheric pressure, means forming a chamber connected at one end to said envelope, and said chamber enclosing said switch and said pressure responsive device.

5. A combination igniter and flame detector comprising, an electric resistance type heating element adapted to be heated to incandescence, a metal envelope enclosing said heating element and slightly spaced therefrom so that said envelope may be heated to ignition temperatures by said heating element, one electrical end of said heating element being grounded to said envelope, a tube connected to the other electrical end of said heating element, said tube extending out of said envelope, a glass to metal seal forming a gas tight connection between said tube and said envelope and insulating said tube electrically from said envelope, a pressure responsive device connected to said tube exteriorly of said envelope so that said envelope, tube and pressure responsive element form a single gas tight system, and a quantity of inert gas filling said system substantially to atmospheric pressure.
